UNITED STATES PATENT OFFICE.

JOHN KANE, OF PHILADELPHIA, PENNSYLVANIA.

STEAM-TRAP.

SPECIFICATION forming part of Letters Patent No. 363,243, dated May 17, 1887.

Application filed April 3, 1886. Renewed November 15, 1886. Serial No. 218,919. (No model.)

To all whom it may concern:

Be it known that I, JOHN KANE, a citizen of the United States, residing in the city and county of Philadelphia, State of Pennsylvania, 5 have invented a new and useful Improvement in Steam-Traps, of which the following is a specification.

My invention has reference to steam-traps; and it consists in certain improvements, all of 10 which are fully set forth in the following specification, and shown in the accompanying drawing, which forms part thereof.

In carrying out my invention I connect a vertical cylinder at top and bottom, by means 15 of flexible pipes, to a steam or condensed water-supply and a water-discharge, the latter of which is provided with a suitable valve. The cylinder is supported by a weighted lever, and when empty the said lever holds it in a 20 raised position; but when sufficiently full to overcome the counter-weight the lever is oscillated and the water-cylinder descends. Simultaneously with said latter action the discharge-valve is opened and the water from the trap is 25 discharged, the action of gravity being assisted by the pressure of steam above the water. The lever has its movements made adjustable by means of cam or eccentric shaped stops, which may be adjusted to limit the throw of the said 30 lever, and also somewhat change its relative position of movement. This lever is provided with an auxiliary weight, which moves with the oscillation of the lever and adds to or reduces the counter-balance, and thereby aids to 35 hold the trap in a raised position until full, and after said trap has been tripped to hold it in its depressed condition until nearly all of the water has been discharged therefrom. A 40 steam-trap of this nature operates automatically, and may be used for discharging condensed water from steam-heating apparatus or exposed steam-pipes without allowing the passage of steam.

The object of my invention is to construct a 45 trap in a simple and cheap manner, and so that it can be adjusted and insured to work under all conditions, and to discharge a maximum quantity of water with a minimum number of movements, thereby reducing the wear 50 upon the working parts and increasing the life of the machine.

In the drawing is shown a front elevation of a steam-trap embodying my improvements, one of its positions being shown in solid lines and the other or discharging position being 55 shown in dotted lines.

A is the hollow receiving-vessel, and is connected at the top by a flexible pipe, B, with the steam and water supply D, and at the bottom by a flexible pipe, C, with the discharge-pipe F, which is furnished with a valve, E. This connection allows the vessel A to be raised or lowered, the said pipes B and C acting as 60 parallel bars and always retaining the vessel in a vertical position.

G is a water-gage, to indicate the amount of water in the vessel A. The vessel A is suspended from the lever H, which is pivoted at h to a fulcrum-plate, J, and its movement is limited and its position of movement controlled 70 by adjustable cam or eccentric shaped stops K, which may be clamped in a rigid position by bolts or screws k .

The supporting lever H is counterweighted at I, so that when the vessel A is empty the 75 weight I depresses its end of the lever and raises the vessel to the position shown in solid lines; but when the vessel is full the water in it overbalances the weight I and oscillates the lever H, causing the vessel to assume the position indicated in dotted lines. The auxiliary weight M is suspended to a plate, L, which is adjustably secured to the lever H, and in the oscillations said auxiliary weight approaches or recedes from the fulcrum h of the 80 lever, thereby assisting or opposing the action of the counter-weight I. The object of this is to retain the vessel A in its raised position until completely full, and then cause it to remain in its depressed position until it is almost empty. This auxiliary weight and its support are made adjustable, whereby the foregoing results may be increased or decreased, 85 as desired. A lever, H, is connected by a rod, N, with the valve-lever P through a pin, 90 p , and slot n , the former working in the latter. If desired, however, the lever H might be positively connected, so that the instant the vessel A commenced to descend the valve E would be opened.

The movements are automatic, and the discharge never takes place until the vessel A is 95 100

full; hence the greatest amount of discharge is insured with the least number of movements.

While I prefer the construction shown, I do not limit myself to the details thereof, as they may be modified in various ways without departing from my invention.

Having now described my invention, what I claim as new, and desire to secure by Letters Patent, is—

10. 1. In a steam-trap, the receiving-vessel and its connecting supply and discharge pipes, in combination with the supporting pivoted and counterweighted lever, a valve in the discharge-pipe, and a slot-and-pin connection between the said valve and lever, whereby the movement of the lever opens the valve at any desired position of its oscillation.
15. 2. In a steam-trap, the receiving-vessel and its connecting supply and discharge pipes, in combination with the supporting pivoted and counterweighted lever, and adjustable cam or eccentric shaped stops to limit and adjust the throw of the lever, substantially as and for the purpose specified.
20. 3. In a steam-trap, the receiving-vessel and its connecting supply and discharge pipes, in combination with the supporting pivoted and counterweighted lever, adjustable stops to limit and adjust the throw of the lever, and
25. 30. an auxiliary weight suspended to the supporting-lever to assist in retaining it in its extreme positions, substantially as and for the purpose specified.
35. 4. In a steam-trap, the receiving-vessel and its connecting supply and discharge pipes, in combination with the supporting pivoted and counterweighted lever, adjustable stops to limit and adjust the throw of the lever, a valve in the discharge-pipe, a connection with the supporting-lever to operate said valve, and an auxiliary weight suspended to the supporting-lever to assist in retaining it in its extreme positions, substantially as and for the purpose specified.
40. 45. 5. In a steam-trap, the receiving-vessel and its connecting supply and discharge pipes, in

combination with the supporting pivoted and counterweighted lever, adjustable stops to limit and adjust the throw of the lever, a valve in the discharge-pipe, a connection with the supporting-lever to operate said valve, and an adjustable auxiliary weight suspended to the supporting-lever to assist in retaining it in its extreme positions, substantially as and for the purpose specified.

6. In a steam-trap, the receiving-vessel and its connecting supply and discharge pipes, in combination with the supporting pivoted and counterweighted lever, adjustable stops to limit and adjust the throw of the lever, a valve in the discharge-pipe, and a connection between said valve and supporting-lever, substantially as and for the purpose specified.

7. The combination of vessel A with flexible supply and discharge pipes B C, suspending lever H having counter-weight I, valve E in the discharge-pipe, lever P to operate the valve, and rod N, connected with the lever H and having a slotted connection with lever P, substantially as and for the purpose specified.

8. The combination of vessel A with flexible supply and discharge pipes B C, suspending lever H, having counter-weight I, valve E in the discharge-pipe, lever P to operate the valve, rod N, connected with the lever H and having a slotted connection with lever P, and adjustable stops K for lever H, substantially as and for the purpose specified.

9. The combination of vessel A with flexible supply and discharge pipes B C, suspending lever H, having counter-weight I, valve E in the discharge-pipe, lever P to operate the valve, rod N, connected with the lever H and having a slotted connection with lever P, adjustable stops K for lever H, adjustable support L, secured to lever H, and auxiliary weight M, suspended therefrom, substantially as and for the purpose specified.

JOHN KANE.
